EDUCATIONAL DEVICE FOR TEACHING SPELLING

Leon Ben Ezra, 810 18th St. NW., Washington, D.C.

Filed Feb. 16, 1961, Ser. No. 63,956

Term of patent 14 years

(Cl. D25—1)

FIG. 1

FIG. 3

FIG. 1 is a front perspective view of an educational device for teaching spelling showing my new design; and FIG. 2 is a plan view thereof; and FIG. 3 is a side view thereof.
The dominant feature of my design resides in the portions shown in full lines.

I claim:

The ornamental design for an educational device for teaching spelling, as shown and described.
